UNITED STATES PATENT OFFICE.

LEON FREIDENRICH, OF NEW YORK, N. Y.

WAISTBAND ATTACHMENT.

SPECIFICATION forming part of Letters Patent No. 352,457, dated November 9, 1886.

Application filed March 19, 1886. Serial No. 195,844. (No model.)

To all whom it may concern:

Be it known that I, LEON FREIDENRICH, a citizen of the United States, residing at New York, in the county of New York, and State 5 of New York, have invented a new and useful Improvement in Waistband Attachments, of which the following is a specification.

My invention relates to waistband attachments for pantaloons; and it consists in the 10 provision of means whereby elasticity shall be imparted to the rear portion of such garments, as hereinafter fully described, and specifically pointed out in the claims.

Referring to the accompanying drawings, in 15 which like letters of reference point out similar parts on each figure, Figure 1 represents a pair of pantaloons with my invention attached thereto. Figs. 2 and 3 are detailed front and rear views of my invention. Fig. 4 20 is an enlarged sectional view.

In the drawings, A represents the ordinary waistband-lining. B is a supplementary band, preferably made of two layers of fabric, b, the upper hemmed or turned-over edge thereof 25 serving as a stay for the upper part of button-holes b'. Said supplementary band is in practice attached at its lower edge to the waistband-lining its full length by a row of stitching, s; but it is not attached to the garment other- 30 wise than along said lower line, by which it will be understood that the whole depth of said band B will be free and form what I herein denominate as a "fly" button-hole band.

Upon the line of such stitching s, I attach a 35 piece of elastic textile fabric, C, of the character known as "stockinet," the upper edge of which is on a right line, the lower edge describing the segment of a circle, whereby such fabric will be wider and deeper at the 40 middle, and from thence diverge toward either end, as plainly shown in the drawings. To the back side of said fabric C are strips D. Said strips have a quality of elasticity different in degree to that of the fabric C.

It will be obvious that the central strip D 45 must be the longer one, and from the central strip each other one on either side will gradually diminish in length relatively to the depth of that portion of the fabric C over which 50 they respectively extend. The strips D are at their upper ends inserted between the lining

A and the supplementary band B, and are firmly held in position by means of stitching s.

The lower curved edge of the fabric C is bound with inelastic material, as shown at e, 55 and between this binding and the fabric C the lower ends of the several strips D are inserted and there held in place by the same stitching, whereby said binding e is attached to the fabric C. 60

For a purpose hereinafter set forth each strip D must be of slightly greater length than the depth of the portion of the fabric C over which each respective strip extends.

My invention is adapted for attachment to 65 that class of boys' pants that are worn without suspenders, and that are in practice buttoned onto a shirt-waist or jacket. It is well known that such apparel is subjected to severe strain and tension from every direction, but 70 principally at and from about the point indicated by the dotted line x x, Fig. 3. Various attempts have been contrived to resist such strain and overcome the risk of tearing the garments and rupturing their fastening devices—such as the insertion of pieces of rubber webbing under button-holes or attachment of strips of like material in various positions; but it is well known that such substances disintegrate by reason of the heat of the person, 75 and from such cause and frequent extension and retraction lose their efficiency. 80

To remedy the defects of existing devices has been the object of my invention.

In carrying out my invention the bound 85 lower curved edge of the fabric C is firmly attached to the rear portion of the pants, and, as will be seen by the drawings, such fabric C will extend down below the point upon which the several members are conjoined, which will 90 be the line of stitching s. Such fabric C must lie in its normal condition unstretched. The lining A is then sewed in place as an inner facing for the waist portion of pants, as common in such garments. 95

When attachment is made by means of button-holes b' to a jacket or waist, the connection thereto will be free to yield under any tension or strain from any direction. (See radially-diverging arrows.) After the fabric C 100 has been stretched to its full extent, if further strain ensues it will be taken up by the strips

D, which will be called into complete operation only after the full elastic properties of the fabric C have been exhausted, and said strips will in their turn resist tension from 5 whatever direction it may come, for it will be understood that being connected only at their upper and lower ends they will be free to be pulled vertically or obliquely, as the case may be. It will also be understood that said strips 10 being longer than that portion of the depth of the fabric C over which they extend, their functional action will not be called into operation until the fabric C has had its elastic properties quite or nearly exhausted. This enables 15 the utilization of fabric C of a very light quality, as it is obvious that if dependence were placed solely for resistance and elasticity upon a piece of such material, adjusted as described and shown, it would have to be thick and be 20 so cumbersome as to be objectionable for attachment in the intended position. The strips D prevent the stockinet from rupture as they take up the strain therefrom as soon as it is extended to a given degree.

25 It is my intention to prepare fly-bands with my improvements attached thereto connected to waistband-linings, as fully illustrated in detail drawings, as an article of manufacture for sale to the trade.

30 Having now fully described my invention, what I claim, and desire to secure by Letters Patent of the United States, is—

1. As a new article of manufacture, a fly 35 waistband provided with button-holes b', and having attached to its lower edge a piece of elastic fabric, C, the lower edge of which is of curvilinear form, in combination with vertical elastic strips D, connected at their upper and lower ends rearwardly to the upper and lower edges of the fabric, substantially as described. 40

2. A fly waistband, B, attached at its lower edge to the waist of a pair of pants and having a downwardly-extending elastic piece of fabric, C, of the greater width at its middle, said elastic C having rearward strips of webbing D arranged in parallel vertical lines, attached only at their upper and lower ends, in combination with a pair of pants, to the seat of which the elastic fabric C is connected along its curved edge, substantially as described. 45

3. The combination, in a supplementary waistband, of the depending elastic piece C, curved at its lower edge, with a series of vertical elastic strips, D, arranged at the rear of the piece C and attached thereto at their upper and lower ends, as and for the purpose intended, substantially as described. 50
